Primary Examiner — Kimberly Barnes(74) *Attorney, Agent, or Firm* — Birchwood IP(57) **CLAIM**

The ornamental design for an air duster, as shown and described.

DESCRIPTION

FIG. 1 is a perspective view of an air duster, showing my new design;

FIG. 2 is another perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The broken lines depict portions of the air duster that form no part of the claimed design.

1 Claim, 8 Drawing Sheets(56)
